[57] CLAIM

The ornamental design for a steering wheel rim and front fale unit, as shown and described.

DESCRIPTION

FIG. 1 is a frontal view of a steering wheel rim and front face unit embodying the novel design;

FIG. 2 is a view from above of the steering wheel rim and front face unit of the novel design;

FIG. 3 is a right side view thereof; and,

FIG. 4 is a left side view thereof.

The rear of the steering wheel rim is understood to be plain and unornamented, and the broken line showing of the rear portion of the steering wheel unit in FIGS. 2,3 and 4 of the drawing is for illustrative purposes only and forms no part of the claimed design.
